UNITED STATES PATENT OFFICE.

RUDOLPH W. MENK, OF JOLIET, ILLINOIS.

AIR CIRCULATOR FOR FURNACES.

Application filed August 13, 1926. Serial No. 128,993.

My present invention relates to furnaces of the hot air type and has more particular reference to a structure of this character that is provided with means whereby the velocity of the air passing through the furnace is increased so as to obtain a maximum efficiency from the furnace. Structures for increasing the velocity of the air in hot-air heating furnaces are commercially known as "boosters" and usually consists of a duct or passageway of annular form disposed with an outlet or orifice within the enclosing shell or casing of the furnace and is provided with a fan or blower whereby a rapidly circulating current of air is created that is discharged within the shell or casing. One of the objects of my invention is the provision of an air-circulator that is so constructed that it may be readily installed in a hot-air heating furnace that is already in use without the necessity of having to tear down or disassemble the furnace structure or substitute a new casing, and the "booster" is so made that it may be readily installed in hot-air heating furnaces of divers types or constructions. It is also an object of my invention to provide a structure which will dependably circulate the air within the furnace shell or casing by causing the air to travel in an upward direction in intimate contact with the walls of the heating unit so as to take therefrom a maximum quantity of the heat units. Other objects of my invention reside in providing an air circulator that is novel in construction, economical to manufacture, compact in arrangement and which is easy to install; and I prefer to accomplish the foregoing objects and carry out my invention in substantially the manner hereinafter fully described and as more particularly pointed out in the claims. Reference is herein made to the accompanying drawings that form a part of this application in which,

Figure 1 is a vertical side elevation of a hot air heating furnace showing my air circulator installed therein.

Figure 2 is a transverse horizontal section taken on line 2—2 of Figure 1 looking in the direction of the arrows.

Figure 3 is a vertical section taken on line 3—3 of Figure 1 and drawn to an enlarged scale to illustrate in detail the construction and arrangement of the parts.

The drawings are in a sense schematic for the purpose of illustrating the principles

of my invention as embodied in a typical or preferred form and throughout the drawings similar reference characters are employed to designate like parts wherever they appear.

The furnace structure comprises the usual cylindrical exterior shell 5 the upper portion of which is closed by a frustum conical hood 6, and the side walls of this hood are provided with discharge openings surrounded by collars 7 or the like, through which the heated air is discharged to the pipes or conduits that distribute the air to the rooms or apartments being heated. The casing 5 surrounds the usual heating-unit 8 that is preferably of cast metal and is spaced from and surrounded by the casing 5 so as to permit the circulation of air between these elements. In the usual form such furnaces receive the cool air through the lower portion of the casing 5 to which it is led by large flues 9 known as the cold-air or return ducts and as this is heated by contact with the surface of the fire-pot said air ascends and is discharged through the ports 7 into the warm air flues for circulation in other portions of the buildings. Unless the capacity of the pipes or ducts leading to and from the casing has been accurately estimated and the fire-pot is of the proper dimensions, there is not a balanced circulation of the air such as will permit efficient heating of the rooms. By installing a "booster" structure such as hereinafter described, I am enabled to increase the velocity of the air within the casing so that the desired flow thereof is obtained.

The circulator which I have designed preferably comprises a blower unit 10 that is actuated by a motor or other power device 11 and takes in air through an inlet opening 12 which may or may not be connected with the return ducts 9 as desired. A substantially fan-shaped or tapered connector 13 extends from the discharge opening of the blower toward the furnace where it leads into the segmental-shaped distributor structure. This distributor structure comprises a substantially vertical wall 14 of such vertical dimensions that it will close an elongated horizontal opening 5^a made in the furnace casing and is secured therein in the manner to be hereinafter described. From the vertical wall 14 there extend upper and lower walls 15 and 16 and from the opposite or inner edge of the lower wall

farthest from the main wall 14 there is another vertical wall 17 disposed substantially parallel with or concentric to the wall 14. These walls are so arranged that when the outer wall 14 is placed so as to close the opening in a furnace shell or casing said walls will project inwardly into the space between the shell or casing and the heating unit and the wall 14 will form a continuation of the wall of the casing.

The upper portion of the wall 14 is bent back upon itself as at 18 to provide a channel into which is inserted the lateral flange 19 on the outer edge of the upper wall to secure it in position. The lower portion of the wall 14 is bent back upon itself as at 20 to provide a channel in which the lateral flange 21 on the outer edge of the lower wall is inserted and secured, and after forming 20 said channel the remaining portion of the metal forming the wall 14 beyond this bend is folded downwardly as at 22 to provide a downwardly facing channel to receive the edge of the casing wall at the bottom of 25 the opening that is cut in the same to install the distributor. As seen in Figure 3, the upper edge of the wall 14 is formed U-shaped in cross-section to receive the flange 19 and the lower edge of the wall is formed 30 S-shaped in section to receive both the flange 20 and the edge of the casing wall below the opening, while the band of metal 23 beyond the bend 22 will be disposed inside the shell. This structure permits the distributor to be 35 inserted into the opening in the casing and lowered until the edge of the shell adjacent the opening enters the channel and the upper portion is then placed against the outer surface of the casing at the upper edge of 40 the opening and may be secured in this position by suitable rivets, bolts, or the like 24. This construction is economical to manufacture and it also permits variations in the thickness of the metal and insures a tight 45 fit in the event the workman fails to take the proper measurements in cutting the opening in the casing, due to the fact that the band 23 of the distributor may be moved up and down telescopically on the casing 50 wall until the desired place is obtained for inserting the rivets or the like.

As will be seen in the drawings (Figure 3), the top and bottom walls 15 and 16 incline towards each other or diverge away 55 from the main or supporting wall 14 so that the distributor appears in frusto-pyramidal shape in section, and the inner edge of the top wall is spaced from the upper edge of the inner vertical wall 17 a distance to 60 provide a restricted elongated passageway or discharge opening 25 of curved shape. The inclination of the top wall 15 is such that the plane thereof is preferably in a line that will intersect the 65 plane of the vertical inner wall 17 at the

upper edge of the latter, but while this is desirable it is not essential. I prefer to provide a depending apron 26 upon the inner portion of top wall 15 that extends down into the distributor chamber to a horizontal plane below the upper edge of the inner wall 17, which prevents the flow of the air through the discharge opening or passageway of the distributor in a horizontal direction, but directs the current of air upwardly in a more or less vertical direction so that it will impinge upon the surface of the heating unit and carry off the heat therefrom to be circulated through the pipes leading from the shell or casing. The construction and arrangement of the parts of this device is such that a venturi is created and the air discharged from the distributor is caused to flow in a positive direction.

While I have herein illustrated and described a specific manner of carrying out my invention, it will be understood that changes may be made for adapting the principles as required, and I therefore desire it understood that all such changes are fully contemplated as coming within the scope of the appended claims. It will also be appreciated that a distributor of this character may be made which employs the top, bottom and inner walls and is secured upon the inner surface of the shell or casing so that the latter provides the outer wall of the distributor, thus providing a structure that may be as a part of the furnace when manufactured, and the furnace sold with such a distributor as an integral part thereof.

What I claim is:—

1. An air circulator for furnaces comprising a segmental shaped walled passageway formed with an outer wall, upper and lower walls extended inwardly from said outer wall, the upper wall being of less width than the lower wall, and an inner wall projecting from the inner edge of the lower wall, the upper edge of which terminates adjacent and spaced from the inner edge of the upper wall whereby to provide a discharge outlet in the upper portion of the structure.

2. An air circulator for furnaces comprising a segmental shaped walled passageway formed with an outer wall, upper and lower walls extended inwardly from said outer wall, the upper wall being of less width than the lower wall, an apron depending from the inner portion of the upper wall, and an inner wall projecting from the inner edge of the lower wall, the upper edge of which terminates adjacent said apron whereby to provide a discharge outlet in the upper portion of the structure.

3. An air circulator for furnaces comprising a segmental shaped walled passageway formed with a vertical outer wall, upper and lower walls inclined inwardly towards each other from opposite edges of said outer wall,

and an inner wall projecting from the inner edge of the lower wall, the upper edge of which is disposed in spaced relation with respect to the inner edge of the upper wall 5 to provide a discharge opening therebetween.

4. An air circulator for furnaces comprising a segmental shaped walled passageway formed with a vertical outer wall, upper and lower walls inclined inwardly towards each 10 other from opposite edges of said outer wall, an apron depending from the inner portion of the upper wall, and an inner substantially vertical wall projecting from the inner edge of the lower wall, the upper edge of which 15 terminates adjacent said apron whereby to provide a discharge outlet in the upper inner portion of the structure.

5. A hot-air heating-furnace comprising a heating unit, a casing surrounding the 20 same and spaced therefrom, distributor pipes leading from the upper portion of said casing, an air-circulator device consisting of a plurality of walls extending inwardly from said casing at an angle thereto 25 and spaced apart to provide a conduit between said casing and said heating unit, the inner portion of said walls approaching each other and separated to provide an elongated outlet from the conduit formed 30 by said walls, and means for delivering a current of air into said conduit.

6. A hot-air heating-furnace comprising a heating unit, a casing surrounding the same and spaced therefrom to provide a 35 return-air heating chamber between the same, distributor pipes leading from the upper portion of said casing, a return-air pipe discharging into said chamber, and an air-circulator in said chamber consisting of 40 a walled conduit formed upon the inner face of said casing and extending inwardly therefrom towards the heating unit and having an elongated discharge opening, 45 through which air is discharged into said chamber, and means for delivering a current of air into said conduit.

7. A hot-air heating-furnace comprising a heating unit, a casing surrounding the same and spaced therefrom, distributor 50 pipes leading from the upper portion of said casing, and an air-circulator consisting of upper and lower spaced walls extending inwardly from said casing, one of said walls having a portion extended towards and 55 spaced from the inner portion of the other

wall to provide an elongated discharge opening in said circulator, and means for delivering air between said walls.

8. A hot-air heating-furnace comprising a heating unit, a casing surrounding the 60 same and spaced therefrom, distributor pipes leading from the upper portion of said casing, and an air-circulator consisting of upper and lower spaced walls extending inwardly from said casing, the inner portions of said walls being extended laterally to the respective walls and towards each other and having their adjacent portions separated horizontally to provide an elongated discharge opening in said circulator, 65 70 and means communicating with the interior of said circulator for delivering a current of air thereto.

9. The combination with the casing of a hot-air heating furnace, and a heating unit 75 within the same and spaced therefrom whereby a air-heating chamber is provided between the same, of a conduit consisting of latterly extending walls mounted upon and consisting of walls at an angle to and extending inwardly from said casing into said heating chamber and provided with an egress port within the casing and an ingress port to receive air from the exterior of the casing whereby air entering said conduit is 80 85 discharged into said chamber.

10. The combination with the casing of a hot-air heating furnace and a heating unit within and spaced therefrom whereby an air-heating chamber is provided between 90 the same, of a conduit within said casing consisting of a hollow walled structure extending from the casing into said chamber and having portions disposed against said casing and secured thereto, said conduit arranged to discharge air into said chamber. 95

11. The combination with the casing of a hot-air heating furnace having an elongated horizontal opening therein, of a walled conduit positioned in said opening and closing 100 the same, said conduit provided with upper and lower flanges that are engaged with said casing upon opposite sides of said opening, and said conduit provided with egress and ingress ports respectively within 105 and without said casing.

Signed at Chicago, in the county of Cook, and State of Illinois, this 7th day of May, 1926.

RUDOLPH W. MENK.
